PENDANT CONTROL SWITCH HANDLE

Reginald A. Bates, Syracuse, N.Y., assignor to Pass & Seymour, Inc., Syracuse, N.Y., a corporation of New York

Filed May 23, 1966, Ser. No. 2,388

Term of patent 14 years

(Cl. D26—13)

The single figure of the drawing is a plan view of the pendant control switch handle. The handle is symmetrical about its longitudinal axis.

I claim:

The ornamental design for a pendant control switch handle, as shown and described.
